United States Patent Office.

GEORGE H. KENDALL, OF SPRINGFIELD, MASSACHUSETTS.

Letters Patent No. 71,310, dated November 26, 1867.

IMPROVED MACHINE FOR PRESSING REINS.

The Schedule referred to in these Letters Patent and making part of the same.

TO ALL WHOM IT MAY CONCERN:

Be it known that I, GEORGE H. KENDALL, of Springfield, Hampden county, Commonwealth of Massachusetts, have invented certain new and useful "Improvements in Folding and Pressing-Machines for Reins;" and I do hereby declare that the following is a full and exact description thereof, reference being had to the accompanying drawings, and to the letters of reference marked thereon. In the drawings—

Figure 1 is a plan view.

Figures 2 and 3 are end views of my improved device.

My invention consists in arranging peculiarly-shaped rollers in connection with a folding device, whereby the leather strips from which the rein is made are first folded and then pass through the rollers, where they are pressed in form, and are ready to be stitched.

In the drawings, the rollers A and B are placed in front of the folders C and D, and are operated by gear-wheels, so as to move in conjunction with each other. The folders consist of plates of metal bent over so as to guide the leather into upper and lower folds. These are placed over and in a groove, E, of the width of the leather, when folded, this groove being cut into the bed of the machine, and being opposite to the opening left between the rollers. In fig. 2 it is shown that the leather a has one of its edges folded by the lower folder C nearly across the entire width of the bottom, while the other edge is folded by the upper folder D, so as to lap over the under fold with its edge a little past the centre, the stitching being afterward run close to this edge and through the centre of the rein lengthways. The leather thus folded passes into the space between the rollers, and is pressed in this form so as to be readily stitched. In fig. 3 is shown the shape of the rollers, the upper one, A, having a groove, F, the width of the rein, and the lower one, B, having a corresponding projection, G, which meshes in with it. The bottom surface of the groove F is varied in depth so as to conform to the sectional shape of the rein, the edge b in the centre being made so as to smooth off the edge of the upper fold. By this means I obtain a great saving in time and work, obviating the necessity of basting the reins before they are stitched, and also forming them much more neatly and accurately, the operation of pressing the reins by means of the rollers requiring no extra time, as it is accomplished by the same operation and in the same time as would otherwise be required to pass the leather through the folders, and even facilitating this last process.

Now, having described my invention, what I claim as new, and desire to secure by Letters Patent, is—

The combination of the rollers A and B, having the grooves F and projection G, with the folders C and D, the parts being arranged and constructed substantially as and for the purpose shown.

G. H. KENDALL.
